CLAIM

The ornamental design for a ballpoint pen, as shown and described.

DESCRIPTION

FIG. 1 is a perspective view of a ballpoint pen showing my new design;

FIG. 2 is a front view thereof, the rear view being a mirror image;

FIG. 3 is a left side view thereof;

FIG. 4 is a right side view thereof;

FIG. 5 is a top plan view thereof;

FIG. 6 is a bottom plan view thereof; and,

FIG. 7 is a perspective view in using state thereof.

The cap is of a transparent body except clip and the part connected with clip. The material is plastic.
